ELECTRIC SWITCH

Albert L. Judson, Portland, Oreg., assignor to
L. R. Teeple Company, Portland, Oreg.

Application May 31, 1939, Serial No. 276,678

7 Claims. (Cl. 200—67)

This invention relates to improvements in electric switches especially adapted to be constructed as a self-contained unit of small dimension.

Objects of the invention are to incorporate in a switch employing magnetic snap-action, a resilient coupling between armature and contacts whereby contact pressure may be increased without increase in operating effort; to incorporate in a switch of this character means for damping any tendency of the moving contact member to rebound; to incorporate in a switch, employing a magnet and a resilient member between armature and switch operator to effect snap-action, adjustable means for varying the spring rate of the resilient member.

The foregoing and other objects will appear as my invention is more fully hereinafter described in the following specification, illustrated in the accompanying drawing, and finally pointed out in the appended claims.

In the drawing:

Figure 1 represents a view in perspective of the entire switch as assembled for application.

Figure 2 represents a view in perspective of the entire switch revealing the terminals or binding posts.

Figure 3 represents a view in perspective of the switch with the cover removed to show the relationship of the working parts.

Figure 4 represents a view of a longitudinal vertical section, taken on the line 4—4 of Figure 1.

Figure 5 is a sectional view taken on the line 5—5 of Figure 4.

Figure 6 represents a view of a section taken on the line 6—6 of Figure 4.

Figure 7 represents a view in perspective of one of the members of the switch mechanism.

Figure 8 represents a view of an enlarged fragment of the section shown in Figure 4.

Figure 9 represents a view of the side of a variant form of switch enclosure.

Figure 10 represents a variant form of the mechanism illustrated in Figure 8.

Referring now more particularly to the drawing:

The essence of this invention resides in the means employed to produce certain novel effects depending upon a unique resolution of spring potentials transmitted through a system of appreciably ponderous levers to provide an enhanced celerity of operation of obvious utility.

The controlled current is carried through conductors comprising binding posts 1 and 2 of conventional characteristics and a spring member 3.

rigidly mounted at one end indicated at 4 and fitted with a suitable contact point 5. Attached to the other side of the spring member 3 is a vertical extension 6 in rigid relationship. A frame 37 is secured to the base 22 and supports the operative members. A switch arm 7 is pivotally supported at 8 and is formed in detail with an extruded portion 9 to form a tongue 10 thereunder which normally extends through an aperture 34 in vertical extension 6 of the member 3. A leaf spring 11 of relatively small size is rigidly attached at one end of the switch arm 7 at 12. The other end of this spring 11 extends to a position 13 above the said vertical extension 6 upon which it constantly bears with comparatively light pressure when the switch is open and a greater pressure when the switch is closed.

On the opposite side of the pivot 8 is an extension of the switch arm 7 formed with a bearing surface 14.

A lever 15 is pivotally supported at 16 and is formed at one extremity with a depending portion 17, in bearing upon said bearing surface 14, and upon the opposite side of the pivot 16 with an extension 18 into which the screw 19 is tapped. Adjustably secured by the screw 19 to the lever 15 are a sliding support 20, illustrated in detail by Figure 7, and a second leaf spring 21.

The whole of this mechanism is secured to a suitable base 22 preferably of folded dielectric material and is enclosed by a suitable cover 23 removably attached to the base 22 by the screws 24 and 25 in a conventional manner.

A plunger 26 extends through a suitable perforation and bearing in the cover 23 formed within the boss 27 and is formed upon its lower extremity with a suitable head 28 adapted to bear upon the free end of the spring 21.

The switch arm 7 is made of a ferrous or magnetic metal and is urged to that limit of its oscillatory movement about the pivot 8 at which the same is shown in Figure 4, by a permanent magnet 29 adjustably supported by means of the screw 30 serving to compress the magnet 29 against a suitable standard 31. A stop 32 conveniently formed upon the standard 31 may be bent to such a position as will provide the proper spacing and relationship between the switch arm 7 and permanent magnet 29.

The device is so adjusted that the contact point 5 engages the contact point 33 at some instant prior to the contact of the switch arm 7 with the stop 32, providing a deflection of the spring 11

beyond that at which the contact of the points 5 and 33 is electrically perfected.

The contact points 5 and 33 are normally held in forcible contact by the pre-strained spring member 3 supplemented by the pressure exerted by the spring 11 upon the vertical extension 6.

The energy required to disengage contacts 5 and 33 is supplied through plunger 26 usually actuated in relatively slow motion. Slow movement of the plunger 26 is transformed into potential energy by deflection of the spring 21 and is accumulated therein until a force is invested sufficient to overcome the said magnetic attraction of the arm 7 by the magnet 29. It naturally follows that when this magnetic attraction has been overcome, the latter will diminish in intensity at a more rapid rate than that at which the force of the spring 21 is attenuated in its movement to the unstrained form.

Since the levers 15, 14 and 7 are necessarily rigid structures and, therefore, of appreciably ponderable mass, the celerity of movement thereof consequent upon the application of a given force will be relatively more sluggish than that celerity with which the relatively light parts will move in response to the same force.

An element of time, therefore, during which the switch arm 7 and the lever 15 may be accelerated to a maximum velocity before electrical contact between the points 5 and 33 is broken, is provided for by an appreciable amplitude of free movement "a" of the switch arm 7 before the tongue 10 thereof engages the extension 6 at the upper extremity of the aperture 34 to disengage the contacts 5 and 33.

Prior to the instant of actual engagement of the switch-arm 7 with the element 3 as just described, the switch arm 7 is motivated at an accelerated velocity by means of three coacting effects.

The resistance to upward movement of the switch-arm 7 offered by the magnet 29 is of rapidly attenuated value. The force of the spring 21 is of relatively more slowly attenuated value so that the effective force thereof actuating the switch-arm 7 is of increasing magnitude. Thirdly, the spring 11, acting to hold the contacts 33 and 5 in engagement with a force supplementing the normal force of the spring member 3, reacts with a supplementary force to accelerate the upward movement of the switch-arm 7 at a rapid rate.

Thus the switch-arm 7 in rapidly accelerated motion operates to disengage the contacts 33 and 5 at such a speed as to eliminate destructive arcing effects.

Another effect which serves to damp out undesirable vibrations of the contact point 5 and the spring 3 upon contact closure results from the relatively dissimilar natural rates of vibration of the springs 3 and 11 and the parts attached thereto. The mutually opposing forces thus constrained are resolved into increased pressures of the electrical contact 5 at the instant of the "make."

Switches of this type being designed for use with condition control apparatus, it is further highly desirable to provide means for regulating the relative values of the two energy components, force and distance, to adapt the switch to the contemplated applications. It is apparent that the mechanical energy input requirement for the operation of the switch is substantially a fixed quantity and that any adjustments of the ampli-

tude of the movement of the plunger 26 may be reflected in commensurate and inverse alteration of the force.

Provision for this adjustment of the stroke of the plunger 26 is provided for by the adjustable spring support 20 which may be extended or retracted longitudinally in contact with the fixed end of the spring 21, to vary the effective length, and resilience of the latter.

It is to be observed that from this novel combination of properties as embodied in the apparatus described, an improved switch of the type is supplied. It is to be especially noticed that various mechanical equivalents for these elements may be readily substituted without evasion of the invention itself. For example, the spring 21 may be omitted without altering the identity of the combination of properties considered to be the invention in the above described combination of elements, but such omission of the spring 21 removes from the switch proper abrupt or snap-acting functions thereof described. Without the spring 21, however, the switch would be operative in a practical sense inasmuch as resilience may be provided in the linkage between prime mover and plunger, or incorporated in the prime mover itself. Furthermore the spring 11, though it imparts desirable features, is not essential to the basic structure of the switch and may therefore be omitted when certain considerations indicate such omission desirable.

Similarly, various mechanical equivalents for the spring 11 may be substituted without altering the identity of the combination of properties considered to be the invention, as, for example, the equivalent shown in Figure 10.

In Figure 9 is shown a switch of variant form in which the elastic element represented by the spring 21' in the switch as described has been disposed externally to effect an economy of dielectric material and conserve space. In this form the plunger 26 is interposed between the externally disposed lever 15' and the bearing corresponding to 14. The operating characteristics, however, are identical with those of the switch described.

In Figure 10 another form of the device embodying the elements of this invention is illustrated, the same being the mechanical equivalent 50 of the device, as represented in Figure 8. In this figure, corresponding parts are represented by parts indicated by similar numerals with prime exponents. In this figure, the functions of the tongue 10 and the spring 11 are inherent in the spring 11', as shown in Figure 10. The delayed action of the spring 3' is provided for by the aperture 34' between the upper and lower limits of which, the spring 11 may move to provide the distance "a'" through which a switch arm 7' 55 though continuously engaged by spring 11' with the piece 6' and hence the contact point 5' may move without effecting motion of the contact point 5'. The vertical portion of arm 7' which embraces space 34' is closely disposed with respect to extension 6' to effect a substantially rigid coupling after spring 11' has deflected through distance "a'". Spring 11' extends through a narrow slot in 6' which permits longitudinal but not vertical relative motion.

What I claim is:

1. An electric switch comprising an elastic member fitted with a contact point at one end and rigidly supported at the other end, a second contact point complementary to the contact point on said elastic member, two binding

posts conductively associated with said contact points, a switch arm pivotally mounted at one end, a permanent magnet disposed in apposition with the free end of said switch arm, a delayed action engagement connecting said switch arm to said elastic member and yieldingly operable means to actuate the said switch arm, said operable means including a resilient member convergent with and attached to a pivoted cam lever bearing upon said switch arm and adjustable spring damping means for rendering said resilient member rigid to a selected degree.

2. A pair of contact-points supported in apposition by means of dielectric and resilient means, a magnet, an oscillatory member of magnetic metal disposed in the field of said magnet, resilient coupling means between said oscillatory member and said contact points, including means to effect a slack motion engagement therewith supplemented by a follower spring biased therebetween, and spring connections through which energy is transmitted to move said oscillatory member in opposition to the attraction of said magnet therefor.

3. A pair of contact points supported and constrained together by means of dielectric and resilient means, a magnet, an oscillatory member of magnetic metal disposed in the field of said magnet, delayed-action connections mutually constraining said oscillatory member and said contact points to sequential motion to interrupt a current through the latter, an operator acting upon said oscillatory member in opposition to said magnet, and a follower spring carried by said oscillatory member and continuously engaging said resilient means adjacent the contact points supported thereby, said spring exerting a bias therebetween serving to spring-load said delayed-action connection to dampen out vibration and augment the tension of said resilient means.

4. In a switch including a magnetic detent and a resilient member adapted for the storage of potential energy imparted by selected external operating means in opposition to said detent, adjusting means associated with said resilient member adapted to compensate said member for the degree of resilience of the particular operating means selected, said adjusting means comprising an adjustable member adapted to impart a selected degree of rigidity to said resil-

ient member by contacting a greater or lesser portion thereof.

5. In a switch in which a magnetic force is opposed by force transmitted through resilient means to effect abrupt separation of contact points normally constrained together, the combination of an oscillatory member acted upon by both said magnetic force and said resilient means and loosely coupled with and thereby adapted to open one of said contact points, spring means supporting and biasing said one of said contacts independently of said member, and additional spring means transmitting the effect of the magnetic force on said oscillatory member to the contact points when in closed position to enhance contact pressure, said additional spring means interposed across said loose coupling and biasing said coupling to a lesser degree when in contact-open position and to a greater degree when in contact-closed position.

6. In a switch employing a switch arm for moving a separately supported and biased contact subsequent to initial contact-opening movement of said switch arm, the combination of a resilient mounting for said contact point and a resilient member coupling said arm and said contact mounting yieldingly prior to and rigidly subsequent to such initial movement to open said contact, said resilient member transmitting pressure from said switch arm to the contact when in contact-closed position to augment the bias of said resilient mounting.

7. In a switch a pair of contact points attached respectively to a base and to a spring arm supported by the base, and normally constrained together by said spring arm, means to open said contacts abruptly including an armature magnetically restrained and coupled with said spring arm loosely when in contact-closed position and a resilient actuator acting upon said armature in opposition to the magnetic restraint to effect separation of said contacts by said armature through said coupling, and means for augmenting the constraint between said contact points when in closed position including a spring interposed between said armature and said spring arm and exerting a bias therebetween of lesser magnitude when in contact-open position and of a greater magnitude when in contact-closed position.

ALBERT L. JUDSON.
